EUGENE H. LANSING, OF WATERFORD, NEW YORK

FELT CLEANING APPARATUS

Application filed April 4, 1929. Serial No. 352,580.

This invention is directed to an improvement in felt cleaning apparatus for use in connection with the felt of paper making machines wherein the felt is subjected to the action of jets of water under pressure to dislodge the impurities in the felt and the water and impurities are removed from the felt by suction boxes.

It is important in felt cleaning apparatus of the type described that the jets of water will be caused to reach the full surface of the felt and as the felt is moving longitudinally, it has been customary to direct the jets of water for travel in a plane transversely of the width of the felt and thus reach the entire surface. This relative movement of the cleaning mechanism requires more or less flexibility in the conduit through which the water is delivered to the mechanism, and in this connection a problem has arisen involved in the support of the flexible conduit free of contact with the felt while at the same time permitting the flexibility essential to permit the spraying apparatus to move to and fro across the felt.

The primary object of the present invention is the provision of means whereby the flexible conduit may be rigidly supported at all times above and in spaced relation with the felt while at the same time permitting that flexibility of the conduit necessary to permit a full transverse reciprocation of the spraying nozzles to insure the delivery of water to the full transverse area of the felt.

The invention is illustrated in the accompanying drawings, in which:

Figure 1 is a view in elevation, partly in section, taken transversely through the supporting frame and felt and illustrating the mounting of the improved spraying apparatus.

Figure 2 is a perspective view of the same.

Figure 3 is a section on line 3—3 of Figure 2.

Figure 4 is a plan, partly in section, showing the means for maintaining the adjacent ends of the rigid conduits for the flexible water conveying pipe.

Figure 5 is a plan view of the apparatus.

Figure 6 is a section on line 6—6 of Figure 5.

The improved apparatus includes a shaft 1 exteriorly threaded throughout its length and terminally mounted for rotation in the side walls 2 of the bed or frame in which the felt 3 is guided in longitudinal movement. A hollow guide member 4 is arranged in concentric spaced relation with the shaft 1, the terminals of the guide being fixed in the frame bars 2 and the guide being formed at the terminal of its vertical diameter with a longitudinally ranging slot 5.

Duplicate spray heads 6 are mounted on and for sliding cooperation with the guide, these spray heads including a hollow semi-circular nozzle section 7 formed for sliding cooperation with the upper portion of the guide and an integral depending traveler 8 shaped to slidably fit the interior of the guide, the traveler having a central interiorly threaded opening 9 for feeding cooperation with the shaft 1. The traveler 8 and hollow section 7 of the spray heads are connected by a web 10 which passes through and slidably fits the walls of the slot 5 in the guide 4.

Depending from and in open communication with each spray head is a spray nozzle 11 which depends from the spray head at substantially right angles to the underlying felt and has its delivery end 12 terminating slightly above the surface of the felt, as indicated more particularly in Figure 6. The spray heads 6 are spaced apart on the guide a distance equaling or slightly greater than half the width of the felt with which they are to cooperate, and the spray heads are maintained in this relative position by a connecting pipe 13 of rigid type, which not only serves to secure the spray heads in relatively fixed relation but also afford a means of fluid communication between them, the pipe for this purpose being secured to and having open communication with the hollow sections 7 of the spray heads.

An important feature of the present invention is the provision of means for rigidly supporting the flexible hose by which the water is supplied to the sprayers, with the support 131

operating at all times immediately above and in spaced relation to the felt and adapted to permit the necessary reciprocating movement of the spray heads in moving to and fro across the felt. The supporting mechanism here shown includes a sleeve-like member 14 rigidly connected to and immediately beyond one of the frame bars 2. A rigid conduit 15, as for example a metal pipe, extends from the sleeve 14 through a slot 16 in the adjacent frame bar 2 and projects transversely of the felt 3 above and in spaced relation thereto. The rigid conduit 15 is terminally connected to the sleeve member 14 by upper and lower straps 17 which maintain the end of the conduit in a fixed horizontal plane at all times while yet permitting a slight pivotal action between the parts. The conduit 15 more or less accurately fits the slot 16 and is, particularly by the lower wall of this slot, supported so that the portion of the conduit overlying the felt is maintained at all times in approximately parallel spaced relation to the upper surface of the felt.

25 A second rigid conduit 18 is connected to that end of the conduit 15 overlying the felt by upper and lower straps 19. These straps, which are of course rigid in themselves, are pivotally connected to the respective conduits 15 and 18 and hold said conduits in spaced relation to permit necessary play of the conduit 18 in operation, as will presently appear. The end of the conduit 18 remote from the conduit 15 has movable connection with the open end of a nipple 20 which extends from and is in open communication with pipe 13. The connection between the nipple and conduit 18 is by upper and lower rigid straps 21 pivotally connected to the respective parts, the open end of the nipple being of reduced diameter and extending within the conduit 18.

45 A flexible conduit in the form of a hose 22 extends into the sleeve 14 through the conduit 15, through the conduit 18 and is frictionally fitted over the free end of the nipple 20, as indicated at 23 in Figure 3.

50 From the above it will be apparent that the hose which supplies the water for the spray nozzles 11 is supported in an inflexible conduit made up of the sections 15 and 18 which, by reason of their relative connections, are maintained above and in parallel spaced relation to the felt, and that the hose is maintained in this plane both when at rest and in all positions of operation.

55 The spraying apparatus, which forms the particular subject-matter of the present application, cooperates in its cleaning function with suction boxes for removing the water and refuse from the felt. These suction boxes are arranged in advance of the spray nozzles or jets in the direction of travel of the felt in order that the water may be delivered to the felt and immediately there-

70 after the felt subjected to the action of the suction boxes. The suction boxes, indicated at 24, underlie the felt and are connected with a suitable source of suction through a conduit 25. The face 26 of each box is in substantial contact with the lower surface of the felt, such face having an opening 27 through which the suction operates on the felt. This opening is comparatively narrow and, if desired and as preferred, a roller 28 may be supported in the plane of the opening to prevent the felt from being drawn down into the opening by the suction, which is a well understood disadvantageous result.

75 The present arrangement contemplates the provision of a suction box for each spray head, with the suction box in alignment with the spray head longitudinally of the felt. The lower portions of the suction boxes, preferably beyond the suction chamber therein, are formed with interiorly threaded openings 29 with which a threaded shaft 30 mounted in the frame bars 2 cooperates to feed the boxes simultaneously and similarly with respect to the feed or movement of the spray heads.

80 As previously stated, the spray heads are spaced apart a distance approximating and at least equal to one-half the width of the felt, and it will be apparent that if the spray heads are reciprocated transversely of the felt, the water from the spray nozzles or jets will be delivered in a stream entirely across the felt. If the shaft 30 for the suction boxes is similarly and simultaneously controlled, as is contemplated, the suction boxes will move in unison with the spray heads.

85 Any conventional means may be constructed to insure the desired reciprocation of the spray heads and suction boxes, such a means being conventionally illustrated in Figure 1 of the drawings. As here shown, the shafts 1 and 30 are provided beyond one frame bar 2, with intermeshing gears 31 and 32 of equal diameter. The shaft 30 is continued beyond its gear 32 and is provided with spaced free pinions 33 and 34 having clutch faces 35 designed to be engaged by a clutch 36 which is keyed for sliding movement on but held against rotary movement with respect to the extension of the shaft 30. The pinions 33 and 34 are spaced apart, so that when the clutch is in cooperation with one, it is free of the other, an intermediate position of the clutch rendering the entire apparatus idle.

90 The pinions 33 and 34 are in driving connection with pinions 37 and 38 respectively, the latter connection being through an intermediate idler 39, the pinions 37 and 38 being mounted upon a power shaft 40 driven by a belt or power wheel 41. Obviously, with the clutch 36 in cooperation with one of the pinions 33 or 34, the shafts 1 and 30 will be similarly and simultaneously driven, the move-

ment of the shafts being of course reversed when one pinion is active with respect to the direction when the other pinion is active due to the interposed idler 39. It will be observed that the shafts 1 and 30 are oppositely threaded, so that the opposite rotations of said shafts, due to the meshing of the gears 31 and 32 will cause spray heads 6 and the suction boxes 24 to simultaneously move in either direction, according to the direction of rotation established by the clutch 36.

As the apparatus in operation is designed to be continuously reciprocated transversely of the felt, means are provided to insure the shifting of the clutch 36 at the appropriate moment. To provide for this, the clutch is provided with an arm 42 which extends through the adjacent frame bar 2 and is there connected to a lever 43 pivotally supported in the frame bar and movable in one direction by a spring 44, the spring being of sufficient strength to move the lever and clutch into clutching relation with a particular pinion. The free end of the lever 43 is connected to a rod 45 which extends through the suction boxes and is provided with an offset 46 beyond one of the boxes, the rod extending through the opposite frame bar to provide a projecting portion 47 for hand control when desired.

The suction boxes are connected for uniform movement by a tie rod or rods 48, and it will be apparent that as the suction boxes reach one end of their travel, as for example the left hand end in Figure 1, the upper end of the lever 43 will be drawn upon against the tension of the spring 44 and thus position the clutch for clutching cooperation with one pinion, as 34. In this position, the free end of the lever is engaged by a pivoted latch 49 to hold the lever in its then position, the latch having a depending projection 50 arranged in the path of movement of the remaining suction box. As the suction boxes reach the opposite limit of travel, that is the right hand edge of the felt, as indicated in Figure 1, the projection 50 is engaged by the suction box, the lever is released through the tripping of the latch and the spring 44 acts to move the clutch in cooperation with the opposing pinion, that is 33, which reverses the movement of the shafts 1 and 30 and causes opposite movement of the spray heads and suction boxes.

It will be apparent from the above description that the spray heads and suction boxes are spaced apart a distance at least equal to one-half the width of the felt 3 and that in the operation of the shafts 1 and 30, the spray heads and suction boxes are moved a distance approximating one-half the width of the felt, so that the respective spray heads and suction boxes alternately occupy a position adjacent the respective frame bars 2

in a position in line with the longitudinal median line of the felt. Thus, the full surface of the felt in a transverse line is subjected to the action of the water through the spray nozzles or jets, and as the felt is advancing longitudinally, this insures a delivery of water and action of the suction boxes throughout the full area of the felt surface.

The important detail in connection with the present invention is the means by which the hose 22 is supported during this movement of the spray heads immediately above and in spaced parallel relation to the upper surface of the felt. This rigid support is provided through the conduits 15 and 18, it being apparent that the conduit 18 moves about the straps 19, that is about the adjacent end of the conduit 15 as a center, during the reciprocation of the spray heads. With the parts properly designed, it will of course be apparent that the conduit 18 moves through an angular path during the reciprocation of the spray heads, the apex or point of which is the free or inner end of the rigid conduit 15. As the spray heads move in a fixed path transverse the felt and as the conduit 18 moves from a position of acute angled relation with the conduit 15 to an obtuse angled relation thereto, it is apparent that the connected ends of the conduits 15 and 18 must, during this movement, be permitted a movement longitudinally of the felt owing to the rigidity of the conduit 18. This movement of the free or inner end of the conduit 15 is permitted by the straps 17 connecting said conduit with the sleeve 14 and by an appropriate length of the slot 16.

The flexible hose 22 provides an unbroken connection or water conduit to the spray heads. The rigid conduits support this hose immediately above and at all times in spaced relation to the felt. There is no possible wear of the hose in operation due to rubbing contact with any part and no possibility of the hose falling on or coming in contact with the felt. Thus, a perfect operation of water delivery to the felt without liability of extreme wear in the parts and an insured and maintained life of the hose are the essential and characteristic results of this detail of the improvement.

What is claimed to be new is:

1. A cleaning apparatus for paper making felt, including spaced spray heads designed for reciprocation transverse the felt, a flexible hose for serving the spray heads, and rigid conduits for supporting the hose above and at all times free of contact with the felt, said conduits being connected for relative movement incident to the reciprocation of the spray heads.

2. A cleaning apparatus for paper making felts, including spaced spray heads adapted for reciprocation transversely of the felt, a

flexible hose for serving the spray heads, and a pair of rigid conduits for receiving and supporting the hose, one of said conduits being mounted for pivotal play longitudinally of the felt and the other of said conduits being mounted for pivotal play transversely of the felt.

3. A felt cleaning apparatus including spaced spray heads adapted for reciprocation transversely of the felt, a flexible hose for serving the spray heads, and two rigid pipe-like conduits through which the hose passes in succession, one of the pipes being supported for pivotal movement beyond the edge of the felt and guided in such pivotal movement in a plane above and in spaced relation to the felt, the other of said pipes being connected for swinging movement with respect to the first mentioned pipe and having pivotal movement with respect to the spray heads.

4. The combination with a paper making felt and frame bars between which said felt is guided, of spray heads arranged in spaced relation and mounted for reciprocation transversely of the felt, a pipe connecting the spray heads, a rigid conduit having one end pivotally connected with said pipe, a second conduit pivotally supported beyond one of the frame bars and extending through an elongated slot in said frame bar, means for swingingly connecting the adjacent ends of said rigid conduits, and a hose extending through the respective conduits and in open communication with said pipe.

5. The combination with a paper making felt and frame bars therefor, of spray heads mounted for reciprocation transversely of the felt, a pipe connection intermediate said spray heads, a sleeve member fixed beyond one of the frame bars, a pipe conduit extending from the sleeve member and through an elongated slot in the adjacent frame bar and terminating substantially at the median line of the felt, rigid straps pivotally connecting said sleeve member and adjacent end of the pipe conduit, a second pipe conduit connected at one end to the pipe connection, rigid straps swingingly connecting the adjacent ends of the respective pipe conduits, and a hose extending through the sleeve member and respective pipe conduits in succession and in open communication with the pipe connection, the support of the respective pipe conduits maintaining the hose in that portion overlying the felt in spaced substantially parallel relation to the felt at all times.

6. A cleaning apparatus for paper making felts having side frame bars, including a threaded shaft supported in the respective frame bars transversely of and above the felt, a hollow guide concentric with the shaft, and spaced spray heads supported on the guide and cooperating with the threaded shaft, the rotation of the shaft feeding the spray heads transversely of the felt, each of

the spray heads including a hollow nozzle chamber partly encircling and bearing on the top of said guide, a spray nozzle communicating with and depending from the chamber, and a traveler integral with the chamber and extending within and fitting the interior of the guide, said traveler having threaded cooperation with the shaft, and means for supplying water to said nozzle chambers.

7. A cleaning apparatus for paper making felts having side frame bars, including a threaded shaft supported in the respective frame bars transversely of and above the felt, a hollow guide concentric with and enclosing the shaft, spray heads supported on the guide and cooperating with the threaded shaft, the rotation of the shaft feeding the spray heads transversely of the felt, a supply conduit connecting said spray heads and maintaining them in spaced relation, the respective spray heads being spaced apart a distance approximating one-half the width of the felt.

8. A cleaning apparatus for paper making felt having side frame bars, including a threaded shaft supported in the respective frame bars transversely of and above the felt, a hollow guide concentric with said shaft, and spray heads each provided with an external nozzle chamber slidably engaging the exterior of said hollow guide and each also provided with a traveller extending into said hollow guide and engaging said threaded shaft so that the rotation of said shaft feeds said spray heads transversely of the felt, and means for supplying water to said nozzle chambers.

In testimony whereof I affix my signature.
